IMPROVEMENT IN CHARGING SHELLS, &c.

TALIAFERRO P. SHAFFNER, OF LOUISVILLE, KENTUCKY.

Letters Patent No. 60,567, dated December 18, 1866.

The Schedule referred to in these Letters Patent and making part of the same.

TO ALL WHOM IT MAY CONCERN:

Be it known that I, TALIAFERRO P. SHAFFNER, of Louisville, in the county of Jefferson, and State of Kentucky, have made new and useful Improvements in Charge for Shells, Torpedoes, &c., which I term Shaffner's shell; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a central section of a shell, charged according to the plan herein described.

Figure 2 is a modification, which maintains the distinctive features of the former, but differs in some of the details.

This improved charge for shells, torpedoes, or mines consists of an explosive liquid, which I term nitro-oleum, (and which will be hereafter described,) in combination with other explosive material or compound.

I have adopted two modes of constructing the charge for shells, employing nitro-oleum, (known in chemistry as nitro-glycerine,) though both are similar in principle. My first plan contemplates the use of small vials, made of hard India rubber, or some equivalent substance, and when filled with nitro-oleum, to be surrounded with nitro or gun-cotton, in the interior of the shell. It would be well to cover each vial with gun-cotton before placing it in the shell, though they may be imbedded in the cotton, so as to prevent concussion that might break them. The object of the nitro-cotton is, in the first place, to produce the first explosion, which will cause the nitro-oleum to explode on the breaking of the vials; and, in the second place, the cotton will serve as a cushion, to prevent the vials from breakage by the concussion caused by the discharge of the shell from the mortar or cannon.

My second plan contemplates the placing of the nitro-oleum in one chamber, which may be made of metal, hard or vulcanized India rubber, or of pure India-rubber bags, or other suitable material. Around the interior chamber of the shell I place elastic India rubber, cut so as to form cavities, appearing like a honey-comb, with holes connecting the cells, and the cells I fill with nitro-cotton, loosely packed. Powder would answer, though it would not be so advantageous as the cotton, as it would not keep equally distributed throughout the cellular parts. The object of the India rubber is to serve as a cushion, to prevent concussion upon the liquid. If nitro-oleum is subjected to a violent concussion it is liable to explode prematurely, or before it passes from the cannon.

The plans above described are intended to prevent the application of a force that would produce an explosion, contemplating the discharge of the contents of the shell only through the means of a percussion cap or a fuse.

In fig. 1, A is the shell and D the vials containing nitro-oleum; C is the gun-cotton or other explosive material surrounding them and in contact with the fuse F, which passes through the fuse plug, B, to the outside, to be ignited on the discharge of the gun. The vials are not necessarily arranged in any particular order, and are introduced through the fuse-plug opening.

Fig. 2 is another form of a shell, generally employed for rifled cannon, and exploded by a percussion cap. A A represent the metal or walls of the shell; B B, the fuse opening; C, the percussion cap; D, the rear-piece, screwed to A A, or otherwise attached; E E are the honey-combed India-rubber cushions; F F are the cells of the India-rubber cushion, filled with nitro-cotton; G G are the walls of the liquid chamber, made, for example, of hard or vulcanized India rubber; H H is the nitro-oleum, nitro-glycerine, or other explosive chemical compound.

The explosive liquid which I call nitro-oleum is obtained by the hereinafter described treatment of glycerine, which is an extract from oleaginous substances, having a specific gravity of about 1.27 at a temperature of 60° Fahrenheit, and having as its constituents carbon 40, hydrogen 9, and oxygen 51. The above treatment of the glycerine consists in compounding it drop by drop with one part nitric acid and two parts sulphuric acid, properly cooled in a freezing mixture, temperature 32° Fahrenheit.

The advantages of this method of charging are as follows: The fuse F ignites the explosive material C, such as nitro or gun-cotton, or gunpowder, which immediately passes throughout the cavity or charge chamber

of the shell, &c., and breaks the vessels containing the nitroleum, producing combustion thereof. A shell or grenade thus charged can, in ordinary artillery practice, contain more metal, and will be fractured with increased force, producing greater destruction than has been heretofore obtained by the use of gunpowder. Large shells thus charged, thrown into a ship, will be calculated with certainty to destroy it. Torpedoes thus charged will increase the cone of force upon the water, enlarging the area of destruction upon the surface, making it greater than has heretofore been obtained by gunpowder. In its application to artillery, mining, demolition of forts, blasting, &c., the cone of the crater will be double at least that attained by gunpowder. The instantaneous combustion of the explosive parts, and their increased power over that of gunpowder, produce the above more effective results.

Having described my invention, what I claim therein as new, and desire to secure by Letters Patent, is—

1. I claim the application of nitro-cotton, (known as gun-cotton,) for the purpose of serving as a cushion and an explosive substance in shells, torpedoes, &c., wherein nitroleum, (in chemistry known as nitro-glycerine,) or other explosive liquid compounds, is used as a charge, substantially as hereinbefore described.
2. I claim the application of India rubber as a cushion lining, for the purpose of lessening the concussion upon the nitroleum or other explosive liquid, substantially as hereinbefore described.
3. I claim the honey-combing of the India rubber, with openings between the cells, for the purpose of perfecting the cushion, and for the object of hastening the spread of fire throughout the said honey-comb cushion lining, substantially as hereinbefore described.

TAL. P. SHAFFNER.
